COMBINED PARTITION-FIXTURE UNIT

Robert L. Davison, New York, N. Y., assignor to
 John B. Pierce Foundation, New York, N. Y., a
 corporation of New York

Application December 20, 1932, Serial No. 648,136

1 Claim. (Cl. 20—1.11)

My present invention relates to building construction and more particularly to an improved combined wall partition and cooking and heating apparatus.

With a view to simplifying the construction of buildings, such as dwelling houses and apartments, and to economize with regard to the cubic displacement of such buildings while yet maintaining the maximum amount of floor space, I have devised the subject matter of the present invention, wherein what may be termed a central heating plant is combined as an element of a unitary structure which embodies, in addition to the central heating unit, a gas or other heating range and a gas plate, as well as having associated therewith and in the same unit a storage tank for hot water. All of the above combined elements are attached directly to or are associated with a partition wall which, in the preferred embodiment of my invention, forms the partition wall or at least a part of the partition wall between two of the main rooms in the dwelling house or apartment, between the living or dining room and the kitchen or scullery.

These various items are combined into a unitary structure which is fabricated in a factory and which may be shipped to the place of installation as a unit and moved into its final position and there permanently forms a part of the building.

The so-called central heating plant, the gas oven and hot water plate, as well as the hot water storage tank, are so placed with relation to each other and to the partition wall as to all be readily accessible and yet occupy the minimum floor space.

Such parts of the unit as are not occupied by the devices above referred to are utilized as space for drawers, cupboards and the like, and the necessary drawer fronts and doors are used as closures for openings necessarily made in the partition wall.

A feature of my invention, therefore, is an improved unitary partition wall and heating and cooking elements.

A novel feature of my invention resides in the direct or indirect attachment to a partition of a plurality of heating, cooking and storage units assembled to occupy a minimum floor space and to be readily accessible to a person using the same.

A feature of my invention is the utilization with a central heating plant attached to one wall of a partition in which doors are provided leading to the central heating plant and which heating plant may be utilized as a central heating plant and an open fireplace.

Further features of my invention and novel details of construction will appear as the description of the invention progresses.

In the accompanying drawings illustrating a preferred embodiment of my invention—

Fig. 1 is a front elevation of a partition wall to which various heating and storage units may be directly or indirectly attached, certain of said units and the position thereof with respect to each other being indicated in dotted lines;

Fig. 2 is a plan view of Fig. 1;

Fig. 3 is a vertical sectional end elevation on the line 3—3 of Fig. 1; and

Fig. 4 is a vertical sectional end elevation on the line 4—4 of Fig. 1.

Referring to the drawings, 10 designates a partition wall or a portion of a partition wall which forms the partition between two of the 15 rooms in a dwelling or apartment or similar structure, such rooms being ordinarily and preferably the living room or dining room, which is located on what may be called the front face of the partition wall 10, and the kitchen or scullery, 20 on what may be designated as the rear face of such partition wall.

At one end of the partition wall 10 is formed either separately therefrom or integral therewith a wall member 11 extending at right angles to 25 the partition wall 10, such wall member 11 being relatively narrow in width. At the end of the partition wall 10, remote from the wall member 11 and separate from or formed integral with the partition wall 10, is a wall member 12 lying 30 parallel to the wall member 11, both the wall members 11 and 12 extending in a direction which may be termed rearward from the front face of the partition wall 10.

Referring specifically to Fig. 1, there is shown 35 in the lower central portion of the partition wall 10 an opening which is closed by doors 13, such doors being swung on hinges 14 as shown, and further such doors 13 are provided with handles 15 and by means of which the doors may be swung 40 on the hinges 14, and also each door 13 is provided with a manually operable ventilator or air inlet 16, to allow air to pass through the doors 13 when the same are in closed position, such air entering therefore into the space behind the 45 doors.

Above the doors 13 and completing the closure of the opening in the partition wall 10 is a grill louvre 17 and through which louvre may pass heated air into the living or dining room above 50 referred to. The louvre 17 forms the exit end of a hot air chamber 18 formed of preferably metallic members 19 backed with heat insulating material 20, as clearly shown in Fig. 4.

Attached to the rear face of the partition wall 55 10 in any convenient manner and within the chamber formed by the rear face of the partition member 10 and the metallic members 19 is arranged a fireplace unit 21, the upper end of such fireplace unit being connected to a flue 22 60

also preferably of metal, which extends through the rear wall of the enclosure 19, as indicated by the numeral 23, and such exit end is connected by the usual piping 24 and 25 to a flue 26 forming part of the dwelling or apartment structure, as clearly shown in Fig. 2.

The heating chamber 18 extends downward on each side of the fireplace unit 21 and the front face of the partition wall 10 is cut away and such cut away portions are closed by louvre members 27, and through which louvre members cold air passes to rise upward as the same is heated by the fireplace unit 21 and the heated air, as will be well understood, passing out through louvre 17 into the living room or dining room, above referred to.

Above the louvre 17 and attached or formed integral with the partition wall 10 is a mantel 28, such mantel being supported rigidly in position by bracket members 29, such being the usual construction.

The mantel 28 extends across the entire width of the partition wall 10 and on one end or the end adjacent to the wall member 12 is provided 25 with a downwardly extending extension 30, such extension having shelf members 31 extending laterally outward therefrom and forming, as will be apparent from an inspection of Fig. 1, shelf members. The downwardly extending member 30 as well as the shelf members 31 are attached to the front face of the wall partition 10, in any desired or approved manner.

Attached to the rear face of the wall partition 10 between the wall member 11 and the air heating enclosure 19 and by means of angle irons 32 is a platform 33, on which is mounted the hot water storage tank 34, which may be connected after installation to any suitable hot water heating device. The platform 33 forms, in addition to 40 a support for the hot water storage tank 34, the upper end of a storage cabinet, access to which is reached through an opening formed in the partition wall 10 below the mantel 28, such opening being closed by a door 35 swung on hinges 36 and 45 provided with the usual operating handle or knob 37.

As will be noted from an inspection of the drawings in connection with the above description, the heating chamber 19 does not extend to 50 a point above or to a point but slightly above the mantel 28, and therefore the space above the fireplace referred to and to the rear of the partition wall 10 is utilized as the housing place for an ordinary gas oven 38, such gas oven being mounted on an angle iron frame 39 in the usual manner.

On top of the front edge of the gas oven 38 is mounted a plate 40 of material preferably similar to the material of the partition wall 10 and thus, 60 as will be readily seen, the gas oven 38 is practically enclosed by partition wall members. Above the fireplace unit and in the space lying between the gas oven 38 and the wall member 12 is arranged the gas plate 41. On the inner face of the wall member 12 and attached to the upper face of the gas oven 38 is arranged a smoke hood 42, the upper end of which is connected to a smoke flue 43, and the smoke hood is connected by piping 44 to a flue 45 and thence to either the flue 26, 70 formed as a part of the building in which the unit is located, or to an independent flue leading to the outer air.

At the connection point between the smoke

hood 42 and the smoke flue 43 is arranged a fan 46 preferably driven by an electric motor housed within the flue 43 and which exhausts into such flue 43 the smoke or odor laden air arising from use of the gas plate 41 as a cooking medium.

Also formed in the upper surface of the smoke hood 42 is a reflector 47 and associated with such reflector is a source of illumination, as a light bulb 48, and which serves to illuminate the space occupied by the gas plate 41.

The space below the gas plate 41 and between the end wall member 12 and the hot air chamber 19 is occupied by any suitable device as for example a drawer 49 and a cupboard 50, the cupboard being closed by a door 51 or other suitable means.

All of the various devices above referred to are assembled in substantially the position shown on the rear face of the partition wall 10 and between the end wall members 11 and 12 and 20 are preferably fabricated as a unit in a factory and separate from the operations of constructing the building in which they are to be located. The devices themselves and the position they occupy with respect to each other are such that 25 the maximum efficiency is obtained in the minimum of space occupied, and economy in the construction of the building or the apartment is obtained in erection expense or in any subsequent remodeling of the said structure.

It is obvious of course that various other devices may be utilized in addition to those already specified, or larger units of the same or different character may be employed, the number and size of the devices employed depending solely on the 35 width as distinguished from the thickness of the partition wall 10. The various devices used are for illustrative purposes only, and while the above is a description of the preferred form of 40 my invention, it will be obvious that I may vary the shape and arrangement as well as the character of the devices utilized within relatively wide limits without departing from the spirit of the invention.

I claim:

A unitary combined partition-wall and housing, comprising two substantially parallelly extending members serving respectively as the opposite face members of the combined partition-wall and housing, elements spatially related to 50 one another and extending from and between said members at a predetermined spacing securing said members unitarily relative to one another, one of said members being provided with an opening arranged to receive and house a 55 heating device, said heating device being disposed within the predetermined spacing intervening between said members, the other of said members being disposed with an opening for the reception of a cooking device accessible through 60 said second-named opening, said cooking device being disposed within said predetermined spacing between said members, said opening in said first-named member being disposed substantially out of alignment with said second-named 65 opening in said other member, said first-named member being otherwise arranged to serve as the wall of a living room or equivalent space of a building, said second-named member being otherwise arranged respectively to serve as the 70 wall of a kitchen or equivalent space of the same building.

ROBERT L. DAVISON.
